UNITED STATES PATENT OFFICE.

GEORGE BALDWIN GERAU, OF MIAMI, FLORIDA, ASSIGNOR OF ONE-HALF TO SOL L. SMITH, OF WILLIAMSBURG, KENTUCKY.

INTERNAL-COMBUSTION ENGINE.

1,352,187.

Specification of Letters Patent. Patented Sept. 7, 1920.

Application filed March 8, 1918. Serial No. 221,246.

To all whom it may concern:

Be it known that I, GEORGE B. GERAU, a citizen of the United States, and a resident of Miami, in the county of Dade and State 5 of Florida, have invented certain new and useful Improvements in Internal-Combustion Engines, of which the following is a specification.

My invention relates to improvements in 10 internal combustion engines, being more particularly an improvement in the valve mechanism for controlling the gases, and consists in the constructions, combinations and arrangements herein described and 15 claimed.

An object of my invention is to provide 20 a shuttle valve piston for an internal combustion engine, the arrangement being such that the necessary valve mechanism is embodied in the piston and operated from the cross head of the connecting rod, thereby 25 eliminating a considerable portion of the weight of the engine ordinarily represented by the cam shafts, lift rods, etc.

Another object of the invention is to 30 provide an engine having a peculiar type of piston and of such a construction as to cooperate with a pair of slide valves operated by the oscillating motion of the cross head 35 as the connecting rod assumes the various angular positions during the revolution of the crank, both the piston and the slide valves having properly arranged ports so disposed to register at the proper times.

Other objects and advantages will appear 40 in the following specification, reference being had to the accompanying drawings, in which:

Figure 1 is a central vertical section of an 45 engine having a piston embodying the improved shuttle valve mechanism,

Fig. 2 is a cross section on the line 2—2 of Fig. 1,

Fig. 3 is a detail section illustrating a 50 slight modification in the arrangement of the shuttle valves, and

Figs. 4 to 8 inclusive, illustrate the various phases of the valve mechanism during one half of a cycle of operation.

By way of preface it should be explained 55 that the shuttle valve mechanism upon which emphasis is laid herein, together with the novel formation of the piston in which it works, comprises the important feature of the invention. The shut-

tle valves, so called because of their peculiar action, are operated by the connecting rod, advantage being taken of the natural oscillating movement of the cross head of the connecting rod when it assumes the various 60 angular positions with respect to the piston during one revolution of the crank.

In carrying out my invention I provide a cylinder 1 which is mounted upon a crank case 2. The cylinder 1 has an intake duct 3 65 embodied therein at one side, and an exhaust passage 4 at the other.

Communication with a suitable type of carburetor is made through an elbow 5 to the intake duct 3, and the manner of arranging the carburetor as well as the duct 3 which in the present instance is shown embodied in the wall of the cylinder, may be changed in any manner as conditions may require. The same applies to the exhaust 70 passage 4. In the present instance a manifold 6 is shown fastened to the outer wall of the cylinder 1 in communication with the exhaust passage. Intake and exhaust ports 7 and 8, respectively, offer communication 75 between the duct and passage and the inside of the cylinder.

Secured on the top of the cylinder 1 is a head 9 which includes an abutment 10 extending down into the cylinder leaving an 80 annular chamber 11. The annular chamber 11 is principally for the purpose of providing a segregated space in which the primary portion of the ignition circuit is completed, by a part of the engine piston, which in itself is of a peculiar and novel construction, 85 as appears more fully below.

The engine piston 12 has a head 13 formed approximately half way of the length of the piston, and the head 13 co-operates with 90 the end of the abutment 10, the explosion chamber 14 of the engine being formed between said head and the end of the abutment. The piston includes an apron 15 which extends below the head 13 as plainly 95 shown in Fig. 1. The space inside of the piston below the head 13 is occupied by the cross head 16 of a connecting rod 17, and the link mechanism of a pair of shuttle valves 18 and 19.

Guide grooves 20 and 21 in the body of the piston 12 accommodate the shuttle valves 18 and 19 which are the intake and 100 exhaust valves respectively. In the present instance, the shuttle valves are arcuate 110

in shape as shown in Fig. 2. In forming the grooves in the piston in which the shuttle valves operate, that portion of the piston carrying the head 13 may be made of a thickness equaling the circular diameter of the arcuate shuttle valves. The apron portion of the piston will then consist of a sleeve fitted over the head portion of the piston, and the two parts secured together.

10 This is simply an illustration of one of the ways in which the piston may be constructed to accommodate the shuttle valves. Instead of making the shuttle valves arcuate, they may be made flat but the particular 15 construction as regards the shape of the shuttle valves is immaterial so far as the present consideration is concerned.

Before proceeding further and in the same connection, attention is directed to Fig. 3.

20 This illustrates a modification in the construction of the piston 12. The guide grooves 20 and 21 may be formed on the outside of the piston or in the apron portion, instead of between the piston walls as shown 25 in Fig. 1. In this instance the valves of course operate in precisely the same manner as will now be set forth.

Intake openings 22 are formed in alignment with each other in the inner and outer 30 walls of the piston 12 at the left side. Similarly, exhaust openings 23 are formed in alignment in the inner and outer walls of the piston at the right side. The exhaust openings 23 are situated in a plane below 35 the intake openings 22, and are adapted to register with the exhaust port 8 during a portion of the downward stroke of the piston so that the burnt gases may pass out under their own impetus.

40 An exhaust port 24 in the exhaust shuttle valve 19 is adapted to move into complete registration with the exhaust openings 23 in the instance just mentioned. An intake port 25 in the intake shuttle valve 18 is adapted to move into complete registration with the intake openings 22, when these openings move into alignment with the intake port 7. This occurs shortly after the exhaust openings and port have performed their function on 45 the downward stroke of the piston.

Links 26 and 27 connect the shuttle valves and cross head 16 together. Each shuttle valve has an ear 28 to which the upper end of each link is connected. Likewise the cross head 16 has ears 29 to which the lower ends of the links are connected. A wrist pin 30 is set in the piston 12, and the cross head rocks on the wrist pin. The lower end of the connecting rod is journaled on the crank 55 31 in the ordinary manner.

Automatic ignition of a compressed charge in the combustion chamber 14, is obtained by a contact plug 32. The plug 32 is screwed into the head of the cylinder so that the end 60 of the plug is exposed in the annular cham-

ber 11. The upper end of the exhaust shuttle valve 19 is adapted to touch the exposed end of the plug 32 and close the primary portion of the ignition circuit when the piston is at the limit of compression.

70 The spark plug 33 is in the secondary portion of the ignition circuit, and when the primary circuit is closed at the moment that the piston is at the extremity of its inward movement, the then completely compressed charge is accordingly ignited. The arrangement of the ignition circuit as just described is shown in one instance in diagrammatic Fig. 4. Here one of the terminals of the battery B and the secondary winding S are 80 grounded to the frame. The other terminal of the battery is connected to the primary winding P, the other end of which is connected to the plug 32. The other terminal of the secondary winding is connected to the spark 85 plug 33. The action can now be readily understood by tracing out the circuits, and will be more fully explained in the description of the diagrams.

Water jackets 34 envelop the cylinder 1, 90 and an extension of the water jackets through the head 9 envelops the spark plug 33. The cylinder walls and end of the abutment 10 are thus effectively cooled. Packing rings 35 inserted in grooves at suitable places in 95 the apron 15 of the piston and on the abutment 10, serve to keep the gases from leaking into the annular chamber at the top and the crank case at the bottom.

100 While the system of oiling the moving parts may be on any approved order, particular provision for oiling the moving surfaces of the shuttle valves is made through numerous minute borings 36 in the valves. These borings are arranged substantially as 105 shown in Fig. 1. It can be readily understood that when the lower exposed parts of the piston become covered with oil as is the case when the splash system is employed, enough oil will be collected in these borings 110 to fill them and convey oil into the surfaces on the inside.

115 The operation of the engine is as follows. Consider Figs. 4 to 8 inclusive which represent various phases in one-half of a cycle of operation of the engine. In Fig. 4 the piston 12 is at the limit of its inward movement with respect to the annular and combustion chambers 11 and 14 respectively, and the compressed charge of gas in the chamber 14 is being exploded by the spark from 120 the plug 33.

125 This spark is made on the closure of the primary circuit through the contact of the end of the shuttle valve 19 with the plug 32 as previously explained. The compressed charge is thus automatically ignited and no elaborate arrangement of timer mechanism is necessary.

Upon explosion of the charge, the piston 130

is forced downwardly. Originally the various openings and ports in the piston and shuttle valves are out of alinement as shown in Fig. 4. The port 25 in the intake shuttle valve operates in a plane above the companion openings 22, while the port 24 in the exhaust shuttle valve operates in a plane below the companion openings 23.

Therefore as the crank 31 proceeds around under the force of explosion, against the head 13, the respective intake and exhaust ports in the shuttle valves gradually come into alinement until the crank has moved through 45°, when all of the openings and ports in the piston and valves are substantially in complete alinement as shown in Fig. 5.

From here on, there is very little change so far as the shifting of the various openings and ports is concerned, since the angular position assumed by the connecting rod 17 between the 45° position in Fig. 5 and the 145° position in Fig. 7, is substantially the same. After the crank 31 has moved through an additional 45° from the position in Fig. 5 to that shown in Fig. 6, the previously alined exhaust openings 23 and port 24, have come into registration with the exhaust port 8 in the cylinder wall when the burnt gas rushes out under its own impetus.

An additional movement of 45° to the position shown in Fig. 7, brings the previously alined intake openings 22 and port 25 into registration with the intake port 7 in the cylinder wall, when a fresh charge of gas enters the explosion chamber partly through the inducement of the partial vacuum created in the explosion chamber. In the meantime, the exhaust openings and port on the other side have begun to move out of registration thus closing off further communication between the explosion chamber and the exhaust passage during the remainder of the present cycle of operation.

In Fig. 8 the crank has moved through 180° and the piston is at the limit of its outward stroke. The respective intake and exhaust openings and intake and exhaust ports are now completely out of registration, and when the crank moves on the up-stroke to compress the charge in the chamber 14, there is no possibility of the charge escaping. When the second charge is fully compressed it is ignited similarly as was the first charge as explained in connection with Fig. 4.

While the construction and arrangement of the engine is that of a generally preferred form, obviously modifications and changes may be made without departing from the spirit of the invention or the scope of the claims.

I claim:

1. An internal combustion engine, comprising a cylinder with an inward extension,

supporting a spark plug and defining an annular space, a piston partially working in the annular space, having a depressed head coöperating with the extension and defining an explosion chamber; and 70 an insulated contact plug engageable by a portion of the piston in the annular space, to complete a primary electrical circuit and produce a spark at the plug in the secondary branch of the circuit. 75

2. In an internal combustion engine, a cylinder having an intake port, an abutment extending into the cylinder leaving an annular chamber and providing an explosion head, a piston having a portion occupying 80 the annular chamber and including a head opposing the explosion head and forming an internal combustion chamber, said piston having intake openings, a connecting rod joined with the piston and including a cross 85 head, a shuttle valve mounted within the body of the piston and having a port normally out of registration with the piston openings, and means including a connecting link joined between the shuttle valve and 90 the cross head, to move the shuttle valve port into registration with the piston openings during the movement of the piston openings into alinement with the cylinder intake port as the connecting rod travels a portion of its 95 stroke.

3. In an internal combustion engine, a cylinder having an inwardly extending abutment leaving an annular chamber and providing an explosion head, a piston including 100 a wall slidable in the annular chamber, said wall having grooves providing valve seats, and gas openings, and a head disposed substantially mid-way of the piston in opposition to the explosion head forming an explosion chamber inside of the piston, a connecting rod including a cross head joined with the piston, a shuttle valve occupying one of the respective grooves each valve having a port normally out of registration with 110 the piston openings, and connecting means between said valves and the cross head, arranged to bring the port of one shuttle valve into registration with the companion piston openings during a portion of the movement 115 of the piston, before bringing the port of the other valve into registration with the companion piston openings.

4. An internal combustion engine, comprising a piston with arcuate valve guide 120 grooves and alining ports associated with each groove, an arcuate valve operatively mounted in each groove, with a port arranged to register with the alining ports to permit the passage of gas; a connecting rod 125 by means of which the piston is actuated, including a cross head, and positive connecting means between the cross head and respective arcuate valves, for reciprocating the valves in said grooves as the position 130

of the cross head changes in the operation of the engine.

5. An internal combustion engine, comprising a piston having a depressed head and valve guide grooves formed substantially centrally of the wall at the sides of the depressed head, aligned ports operatively associated with said grooves being arranged to introduce gas into the chamber partially defined by the depressed head; and reciprocatable valves operatively mounted in said

grooves, with ports arranged to register with the other ports to permit the passage of gas through the wall of the piston into said chamber.

6. The combination, of a relatively fixed engine cylinder with a contact plug, a piston operating in the cylinder, and having a relatively reciprocatively mounted valve member arranged to engage the contact plug to close an electrical circuit.

GEORGE BALDWIN GERAU.
